UNITED STATES PATENT OFFICE

FLORENCE L. GILBERT, OF LOS ANGELES, CALIFORNIA

SOCK

Application filed June 22, 1927. Serial No. 200,527.

My invention relates to socks, and more particularly to short, ornamental socks to be worn preferably with low shoes, and terminating at or near the ankles and provided with means for causing them to fit snugly around the ankles and provided with special trimming or ornamental finish around the top, whereby to make them comfortable and attractive.

10 In order to fully explain my invention, I have shown one practical embodiment thereof on the accompanying sheet of drawings, which I will now describe:

In the embodiment of my invention as here illustrated for descriptive purposes, the body or foot of the sock is designated 5, and may be made of any desired material 25 and in any foot-fitting form. Around the back of said sock I have shown a portion 6, having the wings 7, 7, adapted to be wrapped around the ankle to the front and provided with suitable fastening means. It 30 will be noted that the forward or instep portions of the wings 7, 7 are each formed so that the upper and lower edges converge to the narrow instep fastening portion shown; also, that this fastening portion is 35 located at a point approximately in a line intersecting the instep and heel. This arrangement insures the exposing of the instep, or instep portion of the sock, both above and below the fastening ends of the 40 wings, substantially adding to the pleasing effect of the device when in use on the wearer. I have shown ribbons 8, 8, adapted to be tied into a bow 9, as will be clear from Figs. 3 and 4. These are shaded to indicate black bows, but it will be evident that any desired color may be used to match the other garments worn therewith. Around the top of said sock, I have provided an ornamental finish or trimming here shown 45 in the form of ruffles 10, and in connection therewith a small fastening band 11, which may be used therewith, if desired.

Thus the sock can be applied to the foot and the fastening means adjusted to fit snugly around the ankle, the bow, or other fastening means used, being designed to form not only fastening means, but ornamentation for the foot of the wearer.

The shoe is applied to the foot, over the sock, in the usual manner and is designated 60 12, Fig. 4.

The portion 6, having the wings 7, 7, may, or may not be, made a part of the sock proper, and if made separate to be applied to the foot, around the heel as clearly indicated in Fig. 3, it forms a reinforcement 65 and can be interchangeable with different socks and can be made in different colors to match shoes of different colors, or to correspond to other color patterns worn therewith.

This is also true of the ruffles 10, or other finish ornamentation used around the top of the sock, although it is preferable to make the ruffles or ornamentation a part of the 75 sock. If the reinforcing or heel covering member 6, is made separate from the sock proper, it will be evident that such ruffles or other ornamental finish can be attached thereto, as at 13, and the two can be applied to the foot after the sock proper has been on and the appearance and comfort will be the same.

Thus it will be evident that many changes in details can be made in my invention as 85 here shown and described for illustrative purposes without departing from the spirit thereof, and I do not, therefore, limit my invention to all details as shown, except as I may be limited by the hereto appended 90 claims.

I claim:

1. In combination, a sock, a heel reinforcing member having wing portions to be wrapped around the ankle, and fastening means therefor including a bow for ornamental purposes, said sock being also provided around its top with ornamental ruffles.

2. An ornamental sock including a foot-covering part terminating near the ankle, a reinforcing part at the heel and having wing portions to be wrapped around to the front, fastening means therefor, said fastening means including an ornamental bow.

3. An ornamental sock including in combination, a foot-covering part, a reinforcing part at the heel and having portions to be wrapped around the ankle with ornamental fastening means therefor, and ornamental finishing means around the ankle with securing means therefor.

4. A short sock for women including a foot-covering part terminating around the ankle, an ornamental ankle part formed by gathering the material around the ankle in ruffle-like form, a reinforcing heel part adapted to be wrapped around the ankle, and fastening means therefor, said fastening means including an ornamental bow, substantially as described.

5. A lady's short ornamental sock, adapted to be worn with low shoes, the same being of a length to terminate at approximately the ankle, an ornamental finishing ruffle surrounding the sock adjacent to the ankle, ornamental instep engaging means adapted to pass around the sides and front of the instep portion of the sock comprising a pair of wings and means for fastening the same together at the instep, and supplemental fastening means above the wings associated with the ornamental finishing ruffle, the wings being tapered to expose the sock above and below the same.

6. A lady's short ornamental sock, adapted to be worn with low shoes, the same being of a length to terminate at approximately the ankle, in combination with ornamental fastening means comprising wings adapted to pass over the sides and front of the instep portion of the sock, means for securing the wings over the instep, and supplemental fastening means comprising band portions connected at their rear to the wing portions and free at their front for fastening over the instep at a point above the wings to leave an exposed part of the sock between the wings and said supplemental fastening means.

7. An article of lady's dress apparel, comprising foot-wear which includes a portion to fit under the heel of the wearer in a shoe and provided with wings adapted to be wrapped about the ankle to the instep, leg encircling ornamentation operatively associated therewith, and fastening means for the wings.

8. An article of lady's dress apparel, comprising foot-wear which includes a portion to fit under the heel of the wearer in a shoe and provided with wings adapted to be wrapped about the ankle to the instep, leg encircling ornamentation operatively associated therewith, and fastening means for the wings, the upper edges of the wings inclining downwardly from the heel engaging portion towards the instep, and the leg encircling portion being substantially spaced from said downwardly extending edges.
